C. JESNIG

FLEXIBLE HOLDER FOR PENCILS, ERASERS, AND THE LIKE

Filed Jan. 10, 1924

Inventor:
Charles Jesnig
By W.W. Williamson
M.M.

UNITED STATES PATENT OFFICE.

CHARLES JESNIG, OF PHILADELPHIA, PENNSYLVANIA, ASSIGNOR TO C. JESNIG
MANUFACTURING COMPANY, OF PHILADELPHIA, PENNSYLVANIA.

FLEXIBLE HOLDER FOR PENCILS, ERASERS, AND THE LIKE.

Application filed January 10, 1924. Serial No. 685,811.

To all whom it may concern:

Be it known that I, CHARLES JESNIG, a citizen of the United States, residing at Philadelphia, in the county of Philadelphia and State of Pennsylvania, have invented new and useful Improvements in Flexible Holders for Pencils, Erasers, and the like, of which the following is a specification.

My invention relates to a new and useful improvement in flexible holders for pencils, erasers and the like, and has for its object to provide a simple and effective device of this description adapted to be placed in any convenient position and so anchor a pencil or the like that the pencil may be easily located by the person using the same.

A further object of this invention is to so construct the flexible portion of the holder as to provide for an anchored article being used through a relatively wide range and yet insure its return to the normal position.

A still further object of this invention is to provide a specially constructed base including a cushion for contact with the surface upon which the device may be placed and also to provide a particular form of clip for conveniently attaching a pencil.

With these ends in view, invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

40 Fig. 1, is an elevation of the device a portion of the base being broken away to show the construction thereof.

Fig. 2, is a plan view of the base.

45 Fig. 3, is an enlarged detail section of the edge of the base to more clearly show the manner of securing the cushion ring in position.

50 Fig. 4, is an enlarged detail elevation partly sectional of the central post for securing the members of the base together and for retaining the flexible member.

Fig. 5, is a view similar to Fig. 4 of the thimble carried by the upper end of the flexible member.

Fig. 6, is an enlarged lengthwise section 55 of the pencil clip.

Fig. 7, is a cross section of Fig. 6.

In carrying out my invention as here embodied, 1 represents the base having a circular flange 2 and within this base is located 60 the plate 3, the latter also having a flange as indicated at 4. This flange 4 stands at a slight angle to the plate 3 so that when the cushion ring 5 is placed inside the flange 2 and the plate forced into position the lower 65 edge of the flange 4 will grip the cushion ring and securely hold it in place. The plate 5 also has a cupped up recess 6.

7 represents a post having a shoulder 8 formed on its upper end and also having a 70 reduced threaded shank 9. This post passes through a suitable hole in the center of the base 1, the shoulder resting upon the upper surface of said base while the threaded shank passes through the plate 3 and has a 75 nut 10 run thereon to secure the base and plate together.

The upper portion of the post is hollow in order that the lower end of the flexible member 11 may be secured therein by soldering 80 or other suitable method and a space 12 is provided around the flexible member so as to prevent undue bending of the member at this point, as will be readily understood.

The flexible member 11 is preferably made 85 of spring wire so wound that the coils thereof will normally be drawn in close contact with each other, thus causing it to stand upright as shown yet permitting it to be readily flexed in any direction.

13 represents a thimble secured to the upper end of the flexible member by soldering or otherwise and this thimble has a hole through the top thereof for the passage of a cord 14 and in order that this cord may be 90 readily attached to the thimble a slot 15 is formed in the side of the latter through which the knot 16 may be drawn which knot will hold the cord against withdrawal in the direction of the usual pull thereon.

17 represents a clip formed of sheet metal with sufficient spring to hold a pencil 18 against accidental displacement and this clip has a socket 19 formed therein by cupping up a portion of the metal, said socket 105 serving as a pocket for the reception of the knot 20 upon the opposite end of the cord 14 thus providing a convenient means

2
for attaching the clip to said cord. In use the device is placed in convenient reach of the person or persons using the pencil, the cushion ring 5 preventing the marring of 5 the surface upon which it is set and also providing more or less of a grip upon said surface to prevent the shifting of the device.

When the pencil is picked up for use it may be drawn to a considerable distance 10 by reason of the flexibility of the member 11, yet when released it will be returned to a position of easy access when again needed.

Of course I do not wish to be limited to 15 the exact details of construction as herein shown as these may be varied within the limits of the appended claims without departing from the spirit of my invention.

Having thus fully described my invention, what I claim as new and useful is:—

1. As a new article of manufacture, a flexible pencil holder comprising a base having a flange, a plate also having a flange, the latter fitting within the flange of the 25 base, a cushion ring interposed between said flanges and held in place thereby, a post passing through the base and plate and securing the same together, a flexible member anchored within the post, a thimble secured 30 to the upper end of the flexible member, a cord attached to the thimble, and a clip attached to the outer end of said cord for holding a pencil.

2. In a device of the character described,

a base, a flange formed with said base, a 35 cushion ring fitted within said flange, a plate having a flared flange, said flanges coacting to hold said ring in position, a post passing through the base and plate for securing the same together, and a flexible member anchored within the post, with said post having an enlarged bore at its upper end to allow flexible member to bend on a large radius, relieving wear and excessive tension on spring at one single contact point. 40 45

3. In a device of the character described, the combination of a flanged base, a cushion ring, a flanged plate fitted within the base in such manner as to hold said ring in position by the coaction of the flanges of the base and plate, said plate having a recess, a post having a threaded shank passing through the plate, a nut run upon said shank, said nut fitting within the recess, a shoulder formed with the post and contacting with the upper surface of the base, and a flexible member anchored to the post. 50 55

4. In combination with the flexible member of a device of the character described, a thimble secured to said member, a cord attached to the thimble, and a clip formed of spring material and having a socket formed therein for pocketing a knot upon the outer end of the cord. 60

In testimony whereof, I have hereunto affixed my signature. 65

C. JESNIG.
